MECHANICAL PRESS CONVERTIBLE IN RESPECT TO COMPRESSION OR TENSION DRIVE AND LENGTH OF STROKE

William Klocke, Woodhaven, N. Y.

Application January 21, 1947, Serial No. 723,252

2 Claims. (Cl. 74—40)

1

This invention relates to mechanical presses and provides improvements therein.

The invention provides a crank-driven mechanical press which is convertible to and from a press in which the force which drives the reciprocating tool-carrying slide on its working stroke is applied under compression or under tension, without the substitution of any parts, by the simple reversal of position of one of the parts. It also provides a mechanical crank-driven press in which the stroke of said slide may be lengthened or shortened, without changing the crank or crank-shaft, by the substitution of a simple and inexpensive rocker constituting a part of the slide driving mechanism. The invention further provides a mechanical press of the knuckle-joint type having the characteristics set forth above, and capable of relatively long adjustments of the slide at its bottom-of-the-stroke position and capable of stripping, on the return stroke of the slide, tools from work which clings tenaciously to the tools.

The advantages of the invention are that a large economy is effected in the manufacture of presses and that the press user can obtain the performance of a number of presses with a single press. Press manufacturers can meet the specifications of customers for a press in which the driving force is applied on the working stroke of the slide under compression or under tension with one set of parts for any given size press. He can meet customers' specifications of length of stroke of slide also with one set of parts, one part, a simple rocker being left partially unfinished and holes for a wrist-pin being bored to conform to the length of stroke desired after an order is received.

The press, being of the knuckle-joint type, imparts a slow end-movement to the slide on its working stroke; this enables metal and plastics being worked to conform well to the shape to be imparted thereto by dies, and conserves the dies, the dies ordinarily having about three times the life which they would have in an ordinary crank-press. For plastics work, a press with a slide having a slow end-movement is highly desirable.

The press arranged for application of the driving force to the slide under tension, also contributes to the conservation of the dies, and is highly preferred, if not necessary, when the press is used with some metals or alloys, notably stainless steel. Such a press has a safety feature, in that the bolts which hold in place a bearing-cap on a part under tension may be designed to

2

break when an excessive resistance is encountered by the slide, and thereby save other more expensive press parts.

An embodiment of the invention is illustrated in the accompanying drawings, wherein:

Fig. 1 is a side elevation of said embodiment of press with parts in section;

Fig. 2 is a front elevation thereof;

Fig. 3 is a vertical sectional view of the operating parts of the press, the rocker being shown in a reverse position to that illustrated in Fig. 1;

Fig. 4 is a view of the rocker in side elevation;

Fig. 5 is a diagrammatic view illustrating the movements of the press slide and its driving mechanism;

Fig. 6 is a diagram illustrating the movement of the slide through one press cycle, and also illustrating the movement of the slide of a conventional crank press.

20 Referring to said drawings, numeral 10 designates the press frame, numeral 12 the bed, and numeral 14 the slide. Tools (not shown) are mounted on the bed and slide.

The slide actuating mechanism comprises a 25 crank shaft 16 having a crank 17 thereon, driving rod 19, a rocker 21 and a connecting rod 23. The crank shaft is driven in a suitable manner, as by means of a fly wheel 25 mounted thereon, and a motor and belt, not shown.

30 The rocker 21 has an arm 27 which is pivotally connected to the connecting rod 23 as by means of the pin 30. The rocker has a second arm 32 which is connected to one end of the driving rod 19 as by means of a pin 34.

35 The rocker is pivotally mounted in the press frame in line with the press slide 14 by means of journals 36.

The connecting rod 23 is of adjustable form, a conventional form being shown, comprising 40 two parts, one of which has a ball 38 thereon, forming part of a ball and socket connection with the slide, and having a threaded connection 40 with the other part of the connecting rod. The adjustable connecting rod enables the position of the slide in its bottom-of-the-stroke position, to be adjusted toward or away from the bed 12. The adjustable connecting rod not only provides for adjustment at the bottom-of-the-stroke position of the slide, but also provides a firm connection through which driving force may be applied on the return stroke of the slide, to separate work which clings to a punch or other tool carried by the slide.

50 The driving rod 19 is advantageously provided

with a journal cap 43, attached to the driving rod, around the crank 17, by means of bolts 44. By using bolts which have a yield-point which is less than the yield-point and shear of the other press parts sustaining and transmitting the driving force, a safety feature is provided. When a resistance is encountered by the slide, of such magnitude that the press frame 12 would be excessively strained or broken, the bolts 44 will yield beforehand, and thereby save the press from such an excessive strain. Likewise the crank 17, pins 30, 34 and 36 will be safeguarded against strains which would cause these pins to shear.

The arms 27 and 32 of the rocker 21 are set at a suitable angle to one another, such, for example, as that illustrated in the drawings. As shown in the drawings, the arm 32 is at an angle of 30° from the center line CL of the slide; which passes through the centers of the journal 36 and pin 30, and the arm 32 swings an equal distance on each side of said center line, its arc of swing being bisected by said center line. Said arm 32 may swing at a greater angle than said 30°. Good angles are obtained throughout the working of the parts of the slide driving mechanism through an angle of 90° of movement of said arm 32, 45° on each side of said center line of the slide. The throw of the crank 17 is related to the angularity of the arms of the rocker 21. The throw of crank 17 (that is, the diameter of its crank circle) is equal to the length of the chord of the arc through which the arm 32 moves, said arc being measured at the center of pin 30. With the arm 32 set at an angle of 30° to the slide center line, the arm swings through an angle of 60°, and the length of the chord of said arc of 60° equals the throw of the crank 17. By such an arrangement the slide 14 will be moved to its bottom-of-the-stroke position, with the rocker 21 in the position shown in Fig. 1, when the crank is in one of its dead center positions, and driving force on the working stroke of the slide will be transmitted under compression from the crank to the driving rod. When the rocker 21 is reversed, as shown in Fig. 3, the slide 14 will also be at the bottom-of-the-stroke position when the crank is at its opposite dead center position, and the driving force of the crank 17 will be transmitted on the working stroke of the slide under tension to the driving rod 19. The center of the crank shaft 16 is at a height which approximates the height of the chord of the arc through which the arm 32 moves. As shown, the center of crank shaft 16 is about midway between said chord and the center of the journals 36, for the purpose of better stabilizing the weight at the top of the press.

The rocker 21 may be finished by the press manufacturer except for boring the hole through which the pin 30 passes. When the press manufacturer receives an order for a press having a specified stroke, he can bore the hole for the pin 30 at the proper distance from the center of the journal 36 to give the specified stroke. In Fig. 4 two holes 45 and 46 are indicated with dotted lines, a shorter stroke being imparted to the slide 14 when the pin connecting arm 27 to the connecting rod 23 passes through the hole 45, and a longer stroke being imparted to the slide 14 when the aforesaid pin 30 passes through the hole 46 in the said arm 27.

Operation

Driving force is imparted to the crank shaft 16 through the fly wheel 25, or by other suitable

means. The crank 17, as it rotates, oscillates the rocker 21 on its journals 36, and the rocker, through the connecting rod 23, reciprocates the slide 14 toward and from the bed. At the dead center position c-1 of crank 17, the arm 32 of the rocker 21 is moved to one end of its arc of movement, and the arm 27 of the rocker is moved into alignment with the connecting rod and slide. That is, the centers of journals 36, pin 30 and ball 38 are in alignment, and the press slide 14 is at its bottom-of-the-stroke position. As the crank 17 moves to its opposite dead center position c-2, the arm 32 of the rocker is moved to its opposite extreme position, and the slide 14 is raised to its uppermost position through the rocker arm 27 and the connecting rod 23. In this arrangement, driving force is applied under compression to the driving rod 19.

When it is desired to apply driving force under tension to the driving rod 19, the position of the rocker 21 is reversed. That is, the rocker 21 is turned around so that when the crank 17 is in its dead center position c-1, the slide is at its uppermost position, instead of at its bottom-of-the-stroke position, as in the arrangement prior to the reversal of the position of the rocker 21. In the reversed arrangement of rocker 21 the slide is moved to its bottom-of-the-stroke position when crank 17 is in its dead center position c-2, and in this position, and approaching it, driving force is applied under tension to the driving rod 19 by crank 17.

There is imparted by the mechanism described a slow end movement to the slide 14 on its working stroke, and there is this slow end movement of the slide on its approach to its bottom-of-the-stroke position with the rocker either in a given position, or in a position the reverse thereof.

The movement of the slide 14 through a crank cycle is similar to that of the slide in a knuckle-joint type of press. There is an advantage over the knuckle-joint type of press with the present construction, inasmuch as there is a firm and positive connection of the slide with the slide actuating mechanism, and thus the slide, on its return-stroke, is able to pull out of, or be stripped from, work which clings tightly to the punch or other tool carried by the slide. There is also the further advantage that through the use of the adjustable connecting rod, adjustments of much greater magnitude can be made of the bottom-of-the-stroke position of the slide than with the slide of an ordinary knuckle-joint type press.

In Fig. 6 the movement of the slide through one crank cycle is illustrated by the curve X. The curve designated by the letter Y is a curve for the movement of the slide through one crank cycle of an ordinary crank-press. The slow end-movement of the slide, as it approaches its bottom-of-the-stroke position, clearly appears when curve X is compared with curve Y.

What is claimed is:

1. A mechanical power press, consisting of a crankshaft having a crank thereon, a reciprocating slide having means for mounting a forming tool directly thereon, and means for reciprocating said slide consisting of a rocker pivotally mounted in alignment with said slide, a connecting rod pivotally connected at one end to said slide and at its other end to one arm of said rocker, and a driving-rod connected at one end to said crank and at its other end to a second arm of said rocker, the longitudinal axis of said connecting-rod intersecting the axis on which said rocker turns, and the longitudinal axis of said driving

rod intersecting the axis on which said crank turns, in the bottom-of-the-stroke position of said slide, and the thrust and pull of said driving rod being at substantially right angles to the movement of said slide.

2. A mechanical power press, according to claim 1, wherein said rocker arms are set at an angle to one another, said rocker being reversible on its pivotal connections, and said crank being at one of its dead center positions in one position of said rocker and at its opposite dead center position in the reversed position of said rocker, both coincidental with the position of said slide at its bottom-of-the-stroke position.
